(57) CLAIM

The ornamental design for the pair of high-heeled shoes with toe cap and surface ornamentation, as shown and described.

DESCRIPTION

FIG. 1 is a left side perspective view of the left shoe of a pair of high-heeled shoes with toe cap and surface ornamentation showing my new design;

FIG. 2 is a right side perspective view of the design of FIG. 1; and,

FIG. 3 is the bottom view of the design of FIGS. 1 and 2. The shoe for the right foot of the pair of high-heeled shoes with toe cap and surface ornamentation being the mirror image of the shoe depicted in FIGS. 1, 2, and 3.
